UNITED STATES PATENT OFFICE.

FLORENCE L. GAILEY, OF DETROIT, MICHIGAN.

DESIGN FOR AN EMBLEM, PIN, OR BADGE.

51,551.

Specification for Design.

Patented Dec. 11, 1917.

Application filed October 11, 1917. Serial No. 196,075. Term of patent 3½ years.

To all whom it may concern:

Be it known that I, FLORENCE L. GAILEY, a citizen of the United States, residing at Detroit, in the county of Wayne and State of Michigan, have invented a new, original, and ornamental Design for an Emblem, Pin, or Badge, of which the following is a specification, reference being had to the accompanying drawing, forming part thereof.

The figure is a front view of an emblem, pin or badge illustrating my new design.

I claim:

The ornamental design for an emblem, pin or badge, as shown.

FLORENCE L. GAILEY.

Witnesses:

ANNA M. DORR,
CHAS. W. STAUFFIGER.
